DUPLICATING DEVICE

Filed Feb. 3, 1928

2 Sheets-Sheet 2

UNITED STATES PATENT OFFICE

JOHN D. MCLEOD, OF SASKATOON, SASKATCHEWAN, CANADA

DUPLICATING DEVICE

Application filed February 3, 1928. Serial No. 251,701.

The invention relates to improvements in duplicating devices and an object of the invention is to provide a simple, durable and inexpensive device whereby one can easily and quickly make duplicate sheets of printed material and also to construct the device in a box like form having a cover which can be used as a feeding table and also a pull out drawer in which various devices provided can be stored.

A further object of the invention is to provide a duplicating device embodying a rigid smooth faced work plate, an ink pad overlying the plate and tightly stretched thereon, a stencil sheet overlying the pad and an impression roller.

A further object is to provide an adjustable holder and liner for the upper edge of the sheet to be printed.

With the above more important objects in view, the invention consists essentially in the arrangement and construction of parts hereinafter more particularly described, reference being had to the accompanying drawings, in which:—

Fig. 1 is a perspective view of the duplicating device in open position.

Fig. 2 is a vertical cross sectional view centrally through the same.

Fig. 3 is an enlarged detailed longitudinal sectional view centrally through the device.

Fig. 4 is an enlarged detailed longitudinal sectional view centrally through the work plate, pad and stencil.

Fig. 5 is a vertical sectional view longitudinally and centrally through the upper part of the device and showing a modified way of fastening the ink pad in place.

Fig. 6 is a perspective view of one end of the base board showing the end rod in position.

Fig. 7 is a perspective view of the adjustable holder and liner for the sheets to be printed.

Fig. 8 is a perspective view of the impression roller used.

Fig. 9 is an inverted perspective view of a portion of the cover.

In the drawings like characters of refer-

ence indicate corresponding parts in the several figures.

The body of the duplicating device is in the form of a substantially rectangular sheet metal box 1 which is provided with a pull out sheet metal drawer 2 supplied with an end handle 3, the drawer being of sufficient capacity to hold the various loose appliances used with the device. The box is provided with a sheet metal cover 4, this cover having a comparatively narrow, downturned flange 5 at one edge and a comparatively deep, downturned flange 6 at the opposite edge and two similar tapering downturned end flanges 7 and 8, the end flanges being connected to the ends of the flange 6 and terminating short of the flanges 5 to provide corner slots 8' adapted to receive the upper edge of the box. An angle bar 9 is fastened permanently centrally to the under side of the cover being spaced a slight distance from the flange 5 and this bar co-operates with the flange 5 in preventing displacement of the opened cover.

According to the above arrangement, the cover when placed on the box encloses the same but when one is using the device he can remove the cover and hook the narrow flange 5 over the edge of the box as best shown in Figure 2. At such time, the wide flange 6 supports the then outer side of the cover and the cover forms a convenient feeding table for use in holding the paper to be printed.

Within the box I locate a comparatively thick base board 10 in a location above the drawer and somewhat in from the upper edge of the box, the board being permanently fastened by screws 11 or such like. This base board extends from end to end and side to side of the box. A work plate 12 is placed above the base board and it is necessary that this plate be rigid and have its upper face perfectly smooth. I have found that a sixteen gauge cold rolled steel plate serves my purpose as it does not yield under pressure and gives an absolutely smooth face for the ink pad later described.

In Figures 3 and 4, this plate is shown as somewhat shorter than the length of the box so that it can be readily inserted within the

same from the top. On the work plate, I place an ink pad 13. This pad in Figures 3 and 4 is shown as provided at the ends with end hems 14 and 15 and in the hems I insert cross metal strips 16 and 17. The front end of the work plate is supplied with a number of anchor pins herein shown as transversely aligned spaced screws 18 and the screws pass through the hem 14 and suitable holes 19 provided in the cross strip 16.

After the top end of the ink pad has been fastened by the pins to the work plate, it will be seen that the end of the pad containing the strip 17 extends beyond the other end of the work plate. The advantage of this will be shortly apparent. The stencil sheet 20 employed is placed over the ink pad and it is provided at the top or front end with an attached reinforcing strip 21 and the reinforcing strip is supplied adjoining its upper edge with key hole slots 22, the large ends of which are adapted to receive the heads of the screws 18 and the small ends of which receive the shanks of the screws. This arrangement permits me to readily attach the top end of the stencil sheet in position over the top end of the pad.

Prior to using the device, the pad is inked with a selected stencilling ink, the pad absorbing the ink in the well known manner. The stencil sheet is placed in a typewriter in the well known manner, the typewriter ribbon being removed and the operator manipulates the typewriter keys to cause the type to cut the stencil sheet and so form the stencil. When the pad has been inked and the stencil formed, the stencil sheet is placed over the ink pad in the manner shown, the top end being anchored by the screws and the lower end overlying the cross strip 17 which is at such time in the same plane as the plate 12, it being understood at this time that the plate 12 is removed from the box. One then grabs the lower or bottom edge of the stencil sheet between the thumbs and strip 17 and whilst holding it, swings the strip down to a position underlying the end of the plate 12. This action causes both the ink pad and the stencil sheet to be tightly stretched over the work plate. After the stencil and pad have been stretched, the work plate and parts thereon are placed in the box resting on the base board and will then appear as shown best in Figure 4.

I provide as part of the equipment of the machine, an impression roller 23 fitted with a handle 24. I desire that a good quality rubber roller be provided and that it be accurately ground to give a smooth face.

When a sheet of paper is to be printed, the paper sheet is placed on top of the stencil and one then passes the roller over the upper face of the paper sheet starting at the top end and working towards the bottom. The ink comes up from the ink pad below the sten-

cil sheet through the typed impressions on the latter and onto the paper. I might mention that in doing the work, one should preferably hold say the upper left hand corner of the paper between his finger and thumb and then raise the paper from the stencil sheet to follow the roller as it is being rolled over the sheet to be printed. This avoids any possibility of smudging the printed sheet.

In Figures 5 and 6, I have shown a modified way of holding the ink pad and stencil sheet firmly in place. In this modified form, the work plate is somewhat shorter and it lies directly on the base board and the base board is cross slotted as indicated at 25 and 26 at the ends of the overlying work plate. In each of these slots, I locate an eye 27 and a hook 28 and the hemmed ends of the ink pad are fitted with cross rods 29 and 30 which project beyond the edges of the pad. The pad is held firmly stretched over the work plate by inserting one end of each of the rods in one of the eyes and then catching the other end of each rod in one of the hooks. The upper end of the stencil sheet is anchored to screws 31 corresponding to those 18 and the lower end is wrapped around the lower hem of the ink pad and is so shown in Figure 5.

Where one desires to print cards which are somewhat stiffer than the customary letter paper, I find it convenient to utilize a combined liner and holder as shown in Figure 7. Such appliance comprises two similar U-shaped spring clips 32 and 33 which are connected by a cross rod 34. To the rod I secure a plate 35, the plate having one edge rolled around the rod and fastened thereto by pins 36 and the other edge free and inclining normally upwardly. A spring 37 is coiled around each end of the rod and has one end fastened thereto and the other end fastened to the clip, and the action of the springs is to normally hold the free edge of the plate in an upwardly inclining position. This combination liner and holder is designed to take any desired adjusted position on the upper edge of the box, the clips springing over the sides of the box and holding the appliance in place.

When cards are to be printed on the duplicating device, this combination liner and holder will be located towards the top end of the stencil sheet, the plate 35 overlying the stencil sheet. The card to be printed will be placed with its upper end butting the rolled edge of the plate 35 which serves as a liner for the card. The inclined plate 35 will act to normally hold the card clear of the stencil. When one is using the roller, however, he starts at the end of the card which is lying on the plate 35 and the down pressure exerted on the roller will cause the plate 35 to swing down towards the stencil.

As the roller moves away from the plate 35, the plate will swing up and will accordingly act to raise the card from the stencil and so avoid the possibility of smudging.

5. What I claim as my invention is:—

1. In a duplicating device, a rigid non-perforated base member having a smooth flat surfaced upper face, an ink pad lying on the said face and stretched to lie flat on 10 said face and a stencil sheet for application on the upper face of the pad.

2. In a duplicating device, a rigid non-perforated base member having a smooth flat surfaced upper face, an ink pad lying on said 15 upper face, means for stretching the pad to cause it to lie flat on the said face and a stencil sheet lying on the pad.

3. In a duplicating device, a rigid non-perforated work plate presenting a smooth 20 flat-lying upper face, an ink pad lying on the said upper face and means for stretching the pad over the said face to remove wrinkles.

4. In a duplicating device, a rigid non-perforated work plate presenting a smooth 25 flat-lying upper face, an ink pad lying on the said upper face, means for stretching the pad over the said face to remove wrinkles and a stencil sheet overlying the pad.

5. In a duplicating device, a rigid work 30 plate having a smooth flat-lying face, an ink pad lying on the upper face of the plate and having one end detachably fastened to one end of the plate and the other end extending beyond the other end of the plate and 35 adapted to be folded underneath the plate and permitting of the stretching of the pad over the upper face of the plate.

6. In a duplicating device, a rigid work 40 plate having a smooth flat-lying upper face, an ink pad lying on the upper face of the plate and having one end detachably fastened to one end of the plate and the other end extending beyond the other end of the plate and provided with a hem and a rigid 45 cross strip inserted in the hem, said strip being adapted to be folded underneath the work plate to effect the stretching of the pad over the work plate.

7. In a duplicating device, a rigid work 50 plate having a smooth flat-lying upper face, anchor pins extending upwardly from one end of the plate and in transverse alignment, an ink pad lying on the upper face of the plate and provided at each end with a hem, 55 rigid cross strips contained within the hems, one of said cross strips being provided with holes to receive the pins and anchor one end of the pad to the plate and the other of said strips being foldable beneath the other end 60 of the plate and permitting of the stretching of the pad over the plate.

8. In a duplicating device, the combination 35 with a box-like casing, of a combined liner and holder comprising opposing spring clips adapted to releasably engage the sides

of the casing, a cross rod extending between the clips, an inclined plate having one edge attached permanently to the rod and coiled springs mounted on the ends of the rod, each of said springs having one end fastened to 70 the rod and the other end fastened to the adjacent clip.

Signed at Saskatoon, Sask., this 23rd day of November, 1927.
